UNITED STATES PATENT OFFICE.

JAMES T. COWLEY, OF NEW YORK, N. Y., ASSIGNOR TO THE LAMSON STORE SERVICE COMPANY, OF BOSTON, MASSACHUSETTS.

STORE-SERVICE APPARATUS.

SPECIFICATION forming part of Letters Patent No. 394,557, dated December 18, 1888.

Application filed May 18, 1887. Serial No. 238,676. (No model.)

To all whom it may concern:

Be it known that I, JAMES T. COWLEY, a citizen of the United States, residing in the city, county, and State of New York, have invented certain new and useful Improvements in Store-Service Apparatus, of which the following is a specification.

My invention relates to that class of store-service apparatus in which wheeled carriers travel from a central desk to and past a series of counters, each being arrested automatically at its proper station upon one rail, and are conducted upon another rail back to the central desk; and my invention consists in constructing the parts as fully set forth hereinafter, so as to facilitate the transfer of the carriers from one track to the other at the central desk, and the automatic transfer of each car from the main line to its proper branch line, and to lift each car at its station from the lower rail to the upper return-rail.

In the accompanying drawings, Figure 1 is an elevation of sufficient of a store-service apparatus to illustrate the main features of my invention. Fig. 2 is a plan view of the receiving device at the main desk. Fig. 3 is a transverse section on the line 1 2, Fig. 2, looking in the direction of the arrow. Fig. 4 is a plan view illustrating a modification of the transfer device. Fig. 5 is an elevation of part of the main rail, a branch rail, and switch device of the track leading from the desk to one of the stations. Fig. 6 is a section on the line 3 4, Fig. 5, looking in the direction of the arrow. Fig. 7 is a side view of the switch and adjacent parts in connection with the upper rails. Fig. 8 is a section on the line 5 6, Fig. 7. Fig. 9 is a plan of the parts shown in Figs. 7 and 8. Fig. 10 is an end view of the carrier. Fig. 11 is a side view of the carrier. Fig. 12 is a side elevation of the elevator. Fig. 13 is an end elevation of the elevator. Fig. 14 is a plan of the elevator on the line 7 8.

For the purpose of illustrating my invention I have shown it in connection with a track consisting of two ways, A B, the cashier's desk C, and a single salesman's station, D, connected with the main track by a branch track having ways A' B', the ways A' A' inclining 50 downward toward the desk C, and the ways

B B' inclining toward the salesman's station; but it should be understood that in most instances there are a series of tracks, each extending past a series of salesmen's stations and all converging at a single desk, as is common in some classes of store-service apparatus, where a series of carriers travel upon ways back and forth between the desk and the stations.

My improvements relate more especially to the construction of the receiver at the cashier's desk; to the switch, whereby proper carriers are transferred from the main track to the branch track, according to the stations at which they are to be delivered; to the elevator, by means of which carriers are lifted at the salesman's station from the receiving-way to the upper delivery-way, and to the construction of the carriers. I have therefore illustrated these portions of the apparatus more particularly without attempting to set forth in detail other features of the structure which do not constitute any specific portion of my improvements.

I will first describe the receiver designated by the letter E in Fig. 1, and illustrated in plan, Fig. 2, and in elevation, Fig. 3.

At the receiver the ends of the upper rail, A, and of the lower rail, B, are brought to the same plane, and are both supported from a cross-bar, 2, by brackets 3 4, the cross-bar being supported by a hanger or other device in any suitable manner.

Upon a rod, 6, constituting the lower end of the hanger 5, swings a bracket, F, which carries or is formed to constitute a part of the receiver-track, and being inclined or curved, as shown at f, which provides an effective stop to the onward movement of the carrier, and which bracket may be swung to the position shown in Figs. 2 and 3 to coincide with the rail A, so as to receive a carrier therefrom, or to the position shown in dotted lines, Fig. 2, to coincide with the rail B, so as to deliver a carrier thereto, and the said bracket is provided with a lip, 7, for contacting with stops 8 9 upon or adjacent to the rails A B, to limit the swing of the bracket, so that when the latter is in either position its rail portion will coincide exactly with the opposite track-rail. 100

A spring, 10, is wound around the rod 6 and connected thereto and to the swinging bracket F, and tends to maintain the latter normally in coincidence with the rail A.

5 The bracket 3 is prolonged downward to form a finger, 12, supporting a stop, 13, in position to contact with a stop, 14, upon the carrier, so as to arrest the latter before it reaches the receiver, and the attendant may at any 10 time transfer the carrier from the track A to the receiver by tilting the carrier slightly to one side to remove the stop 14 from the stop 13, and then running it onto the receiving-track, after which the latter is swung to coincide with the track B, and the carrier is pushed onto the latter by hand. By these 15 means each carrier is arrested automatically as it reaches the receiver, so that the contents can be removed and replaced, and is then readily transferred to the receiver and to the delivery-track without the necessity of any nice manipulation by the cashier and without the necessity of removing the carrier from its support, while there is no danger of the derailing 20 of the carriers in any position.

It will be evident that instead of supporting the receiver from a pendent hanger it may be supported upon a standard; and while I have shown a swinging receiver it will be evident that the receiving-track may slide to 30 carry the receiver from the rail A to the rail B. Thus in Fig. 4 I have shown a carriage, G, sliding upon guides 18 18, and carrying the receiver E, having a similar inclined stop, as 35 previously described with reference to Fig. 3, which receiver may be slid from one side to the other, so as to be brought to coincide with either of the rails A B, and of course a spring may be employed to bear against the carrier 40 G, so as to return the receiver E automatically to its normal position in coincidence with the rail A.

After a carrier has been sent from the cashier's desk along the rail B it will continue its 45 movement until it reaches a receiving-station or salesman's station upon the main line, or until it reaches the end of a branch line, to which it should be transferred, and the carriers are provided with means whereby such 50 as are to be transferred to the branch line are automatically deflected to said line while others continue to move upon the main track.

The construction of the switches is illustrated in Figs. 5, 6, 7, 8, and 9, and one construction of carrier for operation in conjunction with the switch is shown in Figs. 10 and 55 11. In said figures, A' and B' represent, respectively, the ends of the upper and lower rails, and A² and B² the switch-rails. Adjacent to each switch the upper rails are supported by yokes or brackets I J, and the lower rails by yokes I' J', each yoke suspended by a rod or wire, 19, from any suitable support, and the lower portion or fork of the yoke supporting the main rail while the upper fork of the yoke I supports a guard, H, and the corresponding fork of the yokes J' 60

support each the end of the adjacent branch rail, which has a lug, 21, Fig. 9, projecting from one side and recessed to receive a pendant rod, 26, constituting one prong of the yoke. Upon each of the rods 26 swings a bracket, 27, which is connected to or forms part of the switch-rail A² or B², which is curved, as shown, and is also notched at the 70 outer end to permit it to be thrown over and coincide at the extreme end with the surface of the main rail, and which then rises, forming an elevation, x, and the heel of the switch-rail practically coincides with the end of the 75 branch rail, with sufficient play between the two to permit the switch-rail to assume either of the positions shown in full and dotted lines, Fig. 9. A spring, 28, is coiled around the rod 26, is fastened at one end to the latter 80 and at the other end to the bracket or switch-rail, and tends to normally maintain the latter out of contact with the main rail in the position shown in dotted lines, Fig. 9.

When a carrier moving in the direction of 90 the arrow, Fig. 5, approaches the switch, the latter will be open, and if the carrier is not to be transferred to the branch track it will pass between the switch and along the main rail; but if it is to be transferred to the branch 95 track the switch-rail will be automatically carried to the position shown in Fig. 9, as set forth hereinafter, and the carrier will ride up onto the elevated portion x of the switch-rail until the flanges of its wheels are raised 100 above the edge of the main rail, and will then move across the main rail onto the switch-rail, and from the latter to the branch rail toward the station.

When a car is traveling from the salesman's 105 station toward the desk in the direction upon the branch rail A' of the arrow, Fig. 7, the side of the carrier is brought against the guard H, which presses laterally against the carrier and forces the latter and the switch-rail A² against the resistance of the spring 28 to the position shown in full lines, Fig. 9, so that the carrier will pass from the switch-rail onto the main-track rail A, after which the 110 spring will carry the switch-rail back to position shown in dotted lines in said figure.

In order that each switch-rail B² may be swung to the position shown in full lines in Fig. 9 when a carrier is to be transferred to the branch rail B', I provide each carrier with 115 a contacting piece or deflector, K, Fig. 11, so arranged that it will contact with the end of the switch B² and move it inward to the position shown in full lines, Fig. 9, before the first wheel of the car is in position to ride onto the 120 switch-rail, and after the car has moved from the switch-rail to the branch rail B' the spring 28 will restore the switch to its open position.

The cars may be differently constructed and provided with different forms of deflectors or contact-pieces; but a preferable construction is illustrated in Figs. 10 and 11. In said figures, L is the frame of the car supported from 125 grooved wheels 29 29, and supporting the re-

ceptacle 30, and provided with the pivoted gates or wings 31, which close the space between the wheel and the frame opposite the hangers of the frame, so as to prevent the cars 5 from being derailed, but which are opened by the contact of lugs 32 upon the gates with properly-disposed fingers when the car is to pass one of the rail-supports, in a manner too well known to need further description.

10 In the frame moves vertically a slide, M, which is maintained normally in an elevated position by means of a spring, 33, and which is provided with a lug or shoulder, 34, for catching upon the shoulder of a detent or pawl, 35, hung to the frame, and when engaging with the lug 34 holding the slide in its lowest position.

The deflector K is fastened to and carried by the slide M, and when the latter is in its 20 lowest position (see dotted lines, Fig. 11) the deflector will not contact with the switch-rail; but when the detent 35 is swung, to permit the slide and the deflector to rise, the deflector will contact with the switch-rail and switch 25 the carrier. The detent 35 is hung to a shaft, 36, provided with an arm, 37, and a spring, 38, tends to swing the shaft and carry the detent toward the lug 34, so that it will automatically engage with the lug when the slide is 30 depressed, and stops N, Figs. 5 and 6, are arranged upon the yokes J', or otherwise suitably supported adjacent to the track, so as to contact with the arms 37 of the carriers, and thereby swing the detent and permit the 35 deflectors K to rise in position to operate the next switch to which the carrier is brought.

As all the carriers are not to be deflected at the same switch, the arms 37 or the stops N are graduated or adjusted (see dotted lines, 40 Figs. 10 and 6) so that only the arms of the carriers that are to be deflected at a switch will strike the preceding stop. I have shown the construction above described for the purpose of illustrating one form of deflector; but 45 it will be evident that different forms of deflectors may be used in connection with carriers and switches described—as, for instance, such different forms as I have illustrated in my application for Letters Patent, Serial No. 50 237,347. It will also be evident that different arrangements of detents and releasing devices may be used, according to the construction and arrangement of the deflector.

The elevator devices are illustrated in 55 detail in Figs. 12, 13, and 14.

The elevator consists of a carriage, P, of any suitable form, sliding upon guides which, as shown, consist of two parallel suspended bars, 55 55, constituting a hanger, the said carriage 60 being raised and lowered so as to bring a rail-section, Q, thereof into coincidence either with the end of the receiving branch rail B' or delivery branch rail A', each of which is supported by means of a bracket extending from 65 the hanger.

The rail-section Q is pivoted by a $\frac{1}{2}$ in. 37, to

the carriage P, so as to take the position shown in either full or dotted lines, Fig. 12, and to the end of the rail-section Q farthest from the branch rails is fastened one end of a flexible 70 elevating-cord, R, which passes around a pulley, 38, carried by an arm, 39, on the carriage P, and also around pulleys 40 41, carried by the hanger, and downward to a suitable reel or other take-up device adjacent to the salesman. Adjacent to the lower track, B', is pivoted a detent-lever, 42, which, when the carriage is in its raised position, is maintained by a spring, 43, in a position (see dotted lines) to contact with and arrest the carriers 80 approaching the station upon the rail B'; but when the carriage is in position to receive a carrier, or in its lower position, the end of a detent (hereinafter more fully described) contacts with the short end of the detent-lever 85 and carries the latter to the position shown in full lines in Fig. 14, so that the car previously arrested upon the rail B' will pass forward onto the carriage.

When the carriage is in the position shown 90 in Fig. 12, a carrier moving in the direction of the arrow along the rail B' will pass onto the pivoted rail-section Q, and the latter being overweighted at the inner end will tilt to the position shown in dotted lines, thereby 95 retaining the carrier in its place; or when the distance between the end of the pivoted rail-section and the pulley 38 is sufficient the carrier may then descend upon the cord R, which will swing downward as a loop and permit the 100 carrier to be lowered to any desired extent. The pivoted rail-section is provided with an arm or projection, 43, which, when said rail-section is tilted, engages with a detent, 44, consisting of a lever pivoted to a pin, 45, and 105 bearing against the side of the projection 43 when the rail-section Q is in the position shown in Fig. 12, and actuated by a spring, 46, so as to slip under the said projection 43 when the rail-section is tilted, and thus the inclined position of said rail-section is maintained.

If the salesman now desires to transfer the carrier to the upper rail, A', he pulls upon the pendent portion of the cord R, and thereby 115 draws the latter to the position shown in dotted lines, Fig. 12, the rail-section Q maintaining its inclined position, so as to hold the carrier in place, and thus elevates the carriage until the outer end of the lever 44 contacts with a finger, 47, adjacent to the rail A', when 120 the lever will be swung to the position shown in Fig. 14 away from below the lug 43, when the tension upon the cord R will swing the rail-section Q to a horizontal position coinciding with the branch rail A', and the car will 125 then run onto said branch rail in the direction of the arrow y and along the latter toward the main track and to the cashier's desk. The lever 44, thus held by the lug 43 in the position shown in Fig. 14, is in position to 130 contact with the lever-detent 42 when the carriage is lowered, so as to cause the latter to

release a carrier stopped by it on the rail B', so as to permit said carrier to run onto the rail-section Q, as before described.

By the construction above described I secure the carrier with absolute safety upon the carriage and prevent its displacement until the carriage is lifted to its proper position, and then, by means of the same cord that elevates the carriage, I restore the rail Q to a position to discharge the carriage onto the rail A'. It will be evident that the carriage may be guided vertically in different ways and may be constructed in different ways, according to the character of the carrier, and I therefore do not limit myself to the specific construction and arrangement of parts shown.

In order to counterbalance the carriage, I use a counterbalance-weight, W, secured to a cord passing over an elevated pulley and downward to the carriage, and I prefer to provide the latter with friction-rollers bearing against the guides, although this is not essential. So, too, the hanger may be provided with a stop, T, which contacts with a portion of the carriage, which may be cushioned or not, so as to limit the upward movement thereof.

In order to close the guards or gates 31 after the car has passed the connections with the tilting rail Q, and to open the gates to allow the car to be restored to the switch-track, I provide the carriage P with a pivoted curved lever, S, which as it contacts with the lugs 32 of the gates closes the gates as the car enters and opens the gates as the car leaves the elevator.

Without limiting myself to the precise construction and arrangement of parts shown, I claim—

1. The combination, with the receiving and delivering rails converging toward the cashier's desk, of the receiver-rail movable in a horizontal plane to coincide with either of the said rails and provided with an inclined end stop, substantially as set forth.

2. The combination, with the receiving and delivering rails of a store-service apparatus, of a receiver arranged at the cashier's desk, and consisting of a bracket pivoted at one end and adapted to coincide at the other end with either of the said rails and provided with an inclined end stop, substantially as set forth.

3. The combination of the receiving and delivering rails, pivoted receiver-rail having an inclined end stop, spring bearing upon the rail to maintain it in coincidence with one of the track-rails, and contact-pieces upon the rails, substantially as and for the purpose set forth.

4. The combination, with the main rail of a store-service apparatus, of a branch rail and a switch-rail movable to and from the top of the main rail, and provided with an elevated portion, x, for raising the carrier-wheels with their flanges above the main rail, substantially as set forth.

5. The combination of the continuous main rail, branch rail, and a switch-rail movable

laterally to and from the main rail, and a spring bearing on the switch-rail to maintain it normally from contact with the main rail, 70 and said switch-rail provided with an elevated portion, x, substantially as set forth.

6. The combination of the main rail, branch rail, movable switch-rail, spring, and a carrier provided with a deflector for contacting directly with and setting the switch-rail, 75 substantially as and for the purpose set forth.

7. The combination, with the main rail, the branch rails, and switches of a store-service apparatus, of carriers provided with movable 80 deflectors for operating the switches, and graduated stops adjacent to the rails for setting the deflectors, the parts being graduated to set the proper deflector only prior to the car reaching the switch to be deflected, substantially as set forth.

8. The combination, with the car of a store-service apparatus, of a movable deflector and detent for holding it in one position, and stops adjacent to the rails for operating said detent 90 to release the deflector and permit it to assume another position, substantially as set forth.

9. The combination, with the frame of a carrier, of a slide, a deflector connected thereto, 95 a spring operating the slide, a detent, and stops adjacent to the rails for operating upon said detent to release the slide, substantially as set forth.

10. The combination, with the main, branch, and pivoted switch rails of a store-service apparatus, of a spring for maintaining the switch-rails normally from contact with the main rails, stops adjacent to the rails, and deflectors carried by the cars and movable vertically by the action of said stops, substantially as and for the purpose set forth.

11. The combination, with the main and branch rails, of a yoke, J', provided with a vertical rod, 26, a switch-rail pivoted to said rod, and a spring bearing upon the switch-rail, substantially as and for the purpose set forth.

12. The combination, with the upper and lower rails, of a vertically-movable carriage 115 supporting a tilting rail-section connected at one end to an elevating-cord, substantially as set forth.

13. The combination of the upper and lower rails, a vertically-movable carriage supporting a tilting rail-section, a detent engaging with and holding the section in position when tilted, and a bearing adjacent to the upper rail for contacting with and withdrawing the detent to release the tilting rail-section when 120 the latter is adjacent to the end of the upper rail, substantially as set forth.

14. The combination, with the upper and lower rails, vertically-movable carriage, and tilting rail-section thereon, of a cord connected 130 with the end of the rail-section extending backward toward the end of the carriage and upward and over a pulley and downward to a salesman's station, substantially as set forth.

15. The combination, with the vertically-movable carriage and tilting rail-section pivoted thereto and detent for holding said section in its tilted position, of a cord connected to the rail-section and passing upward from a pulley and downward to the salesman's station, substantially as set forth.
16. The combination of the vertically-movable carriage, tilting rail-section, elevating cord, and pulley 38, supporting the cord in a position to receive the carrier, substantially as and for the purpose set forth.
17. The combination, with the vertically-movable carriage and tilting rail-section and cord, of a lever, S, substantially as and for the purpose set forth.
18. The combination, with the vertically-movable carriage and tilting rail-section and fixed upper and lower tracks, of a movable detent, 42, and spring for maintaining it in a position to arrest the carriers upon the lower track, and contact-piece, as 45, on the carriage for operating said detent and holding said rail-section in its tilted position, substantially as set forth.
19. The combination, with a carrier, a vertically-movable carriage, and tilting rail-section, of an elevating-cord connected to the end of the tilting rail-section to form a continuation thereof, whereby the carrier is supported by said cord and rail-section, substantially as described.
20. The combination, with the tracks of a store-service, a vertically-movable carriage, and its tilting rail-section having a projection, 35 43, of a detent mounted on the carriage and adapted to engage the rail-section to hold it tilted, and a pivoted detent, 42, having its end located in the path of the detent on the carriage, whereby the latter detent is moved to 40 allow the rail-section to move into alignment with one of the tracks, substantially as described.

In testimony whereof I have signed my name to this specification in the presence of 45 two subscribing witnesses.

JAMES T. COWLEY.

Witnesses:
